UNITED STATES PATENT OFFICE.

ALBERT C. KILLIUS, OF SPOKANE, WASHINGTON, ASSIGNOR OF ONE-HALF TO WASHINGTON MCCORMICK, OF HILLYARD, WASHINGTON.

TROUSERS-SUPPORTER.

No. 926,259.

Specification of Letters Patent.

Patented June 29, 1909.

Application filed December 30, 1907. Serial No. 408,672.

To all whom it may concern:

Be it known that I, ALBERT C. KILLIUS, a citizen of the United States, residing at Spokane, in the county of Spokane and State of 5 Washington, have invented a new and useful Trousers-Supporter, of which the following is a specification.

This invention relates to a device for supporting trousers; and has for its object to 10 provide a simple and certain means for retaining the trousers on the person in proper position without the use of suspenders or a tight encircling belt, the former of which gives an undress appearance to a man, while 15 the latter to properly hold up the trousers must be drawn so tightly around the body as to be uncomfortable and more or less injurious because of its compression.

In the supporter of the present invention, 20 the trousers are upheld by a pair of resiliently connected plates, pads or equivalent means of proper shape fitted to the hips above the pelvic bones, the joining means being a spring rod or band which passes behind the body and, by its elasticity, holds 25 the plates, pressed against the trousers, securely in the depressions in the body above the innominate bones. The spring band or rod does not touch the body, but is upheld 30 by flexible loops thereon attached to buttons on the rear of the trousers, or by other convenient means. The resiliently connected plates may be used alone but the supporter is preferably worn in combination with a 35 belt to which the spring band connecting the plates is attached, and which is adapted to pass around the body and be loosely fastened in front. The main object of the belt is to improve the appearance of the person wearing 40 the supporter by rendering the spring band and more or less of the plates invisible by covering them with the belt.

In the accompanying drawing; Figure 1 is a side view of the supporter combined 45 with the belt as it appears when placed around the waist. Fig. 2 is a rear view showing the supporter without the belt disengaged and about to be applied about the waist. Fig. 3 is a perspective view of the 50 supporter complete. Fig. 4 is a similar view showing a slightly modified construction. Fig. 5 is a cross sectional view on the line A—A of Fig. 3. Fig. 6 is a view of a modified detail. Fig. 7 is a sectional view of 55 another modification. Fig. 8 is a sectional

view on the line x—x of Fig. 6 looking in the direction indicated by the arrow.

Similar reference numerals are used for the same parts in all the figures.

The numeral 1 indicates a curved spring 60 band, made preferably of steel, and having a round, square, flat or other cross sectional shape as circumstances or taste may dictate. One form of this band is shown in Fig. 3 and another in Fig. 4. The ends 2 of the band 1 65 may be flattened as shown in Fig. 4, or provided with tips 3 as represented in Fig. 6. The ends of the spring band 1 are each fixed or adjustably attached to the outer side of a curved plate 4 shaped to conform to the side 70 of the body immediately above the brim of the pelvis. The curved plates 4 may be solid, or provided with perforations and made of any suitable material, preferably leather or vulcanized rubber. In place of a 75 plate, a pad or cushion 5 may be employed as is shown in Fig. 7.

Fastened to the spring bar 1 between the hip plates 4 and on the outside thereof is a belt 6 such as is usually worn by men as a 80 substitute for suspenders, with an ordinary buckle on one end for fastening the belt in front. A strip of leather 7 is placed inside the band 1, reaching from one plate to the other, and stitched at its edges to the belt, 85 thus inclosing the band in a sheath and effectually hiding it from view when the supporter is on the body, the belt covers also a part of each hip plate 4.

To use the trousers supporter, the trousers 90 are first fastened and then pulled up to the proper height, after which the supporter is passed behind the body and with the plates 4 grasped by the hands, the band 1 is expanded sufficiently to permit the plates being seated against the sides of the body above the innominate bones. The ends of the belt are then brought around to the front of the body and buckled, sufficient tension 95 only being employed to keep the front of the 100 belt in place. The tension of the spring band 1 and the shape of the plates 4 are such that the plates cannot be drawn over the edge of the pelvis by the weight of the trousers, nor by movements of the body, 105 they, therefore, hold the trousers in proper position and with a perfect hang. The spring band is so shaped that the belt does not come in contact with the wearer's back and as the belt is loosely fastened, there is 110

- perfect circulation and freedom from pressure around the waist. Nor is the clothing bound closely against the body except at a small place on each side beneath the plates 4. 5 The muscles of the back and abdomen are thus unfettered and freedom of action assured.

When the supporter is worn without the belt, it is applied as shown in Fig. 2 and, to 10 prevent the band 1 from dropping, one or more flexible loops 8 are fastened thereto which are attached to the back buttons of the trousers, or if desired other means may be used in place of the flexible loops. Similar loops 8^a are also used when the belt is 15 worn, the same being attached to buttons properly arranged on the trousers.

One means of adjusting the plates 4 in line with the spring band is represented in Fig. 20 4 and consists of a series of threaded perforations 9 in the plates, horizontally disposed, for screws 10 passing through holes in the flattened ends of the band. Another 25 form of adjustment is disclosed in Fig. 6. Here a ball 11 is fastened to the plate 4 and the tip 3 on the end of the spring band longitudinally slotted and provided with a 30 spherical ball seat. A screw 12 connects the slotted ends of the tip and by turning this screw the friction between the ball and the tip may be adjusted to suit.

The forward ends of the plates 4 have 35 openings 13 in which a short strap or belt may be temporarily attached when the longer belt 6 is not used, and brought around the front of the body. This belt is not necessary to retain the supporter in place but it may be desired by some for use or appearance. As a rule, the trousers supporter with the 40 belt 6 attached will be worn during the season of the year when the vest is discarded and only a coat is worn and even this garment omitted at times. The supporter without the belt may be worn in cold weather 45 the coat and vest serving to hide the spring band and the hip plates.

When the trousers are to be removed it is only necessary to unbutton and push them down as usual, the spring band 1 will yield 50 under the pressure and the supporter will hang from the loops 8.

Having thus described my invention, what I claim as new and desire to secure by Letters Patent is:

1. A trousers supporter comprising a 55 curved spring band having spaced ends, and a pressure plate attached to each end of said spring band adapted to bear against the trousers at each side of the body above the innominate bones and conforming to the 60 shape of the said bones.

2. A trousers supporter comprising a curved spring band having spaced ends, and a pressure plate adjustably attached to each 65 end of said spring band.

3. A trousers supporter comprising a curved spring band having flattened ends, a pressure plate adjustably attached to each of said flattened ends, and upholding means 70 on the band between the plates.

4. A trousers supporter comprising a curved spring band provided with spaced ends, a tip on each end of said band, a pressure plate adjustably attached to each tip and having an opening in its forward end, 75 and loops fastened to said spring band.

5. A trousers supporter comprising a curved spring band, a pressure plate attached to each end of said spring band arranged to bear against the trousers at each 80 side of the body above the pelvic bones and conforming to the shape of the body at the point of contact, and a waist belt attached to said band between the plates and adapted to fasten in front of the body.

6. A trousers supporter comprising a curved spring band, a pressure plate adjustably attached to each end of said band, a belt on the outside of the trousers supporter and a strip of suitable flexible material on the inside thereof extending between 90 said plates in front of the band and fastened to the belt at its edges.

7. A trousers supporter comprising a curved spring band, a pressure plate adjustably attached to each end of said band and a waist belt having fastened thereto on its inner side at the edges a strip of suitable flexible material to form a sheath for the 95 spring band between the pressure plates.

In testimony that I claim the foregoing as my own, I have hereto affixed my signature in the presence of two witnesses.

ALBERT C. KILLIUS.
